UNITED STATES PATENT OFFICE.

FRED A. BAKER, OF ROANN, INDIANA.

WINDMILL.

SPECIFICATION forming part of Letters Patent No. 352,108, dated November 9, 1886.

Application filed April 1, 1886. Serial No. 197,424. (No model.)

To all whom it may concern:

Be it known that I, FRED A. BAKER, a citizen of the United States, residing at Roann, in the county of Wabash and State of Indiana, have invented certain new and useful Improvements in Windmills, of which the following is a specification, reference being had thereto to the accompanying drawings.

This invention has relation to improvements in windmills; and it consists in the novel construction and arrangement of devices, as will be hereinafter fully explained, and particularly pointed out in the appended claims.

The annexed drawings, to which reference is made, fully illustrate my invention, in which—

Figure 1 represents a vertical sectional view of my device. Fig. 2 is a horizontal sectional view taken on line $x-x$, Fig. 1. Fig. 3 is a top view with the wheel removed. Fig. 4 is a detail view of a section of the wheel.

Referring by letter to the accompanying drawings, A designates the tubular support for the operating mechanism which extends through a central opening in the platform of the tower B, and is braced by rods a, having adjusting turn-buckles b, whereby the wind-wheel may be leveled at will. This tubular support is provided at its upper end with a circular flanged bearing, c, and a collar, d, below the same.

Above the flanged tubular portion extends a tubular bearing, e, on which is mounted a casting, C, having at its lower end a circular flange, f, and a roller, g, which travels upon the circular flange of the lower tubular portion. This casting C is provided with two arms, h and i, the former extending rearwardly and the latter laterally, to each of which are connected cords or chains kk' , that pass around pulleys ll' , journaled in brackets on the vane D, thence over pulleys mm' , journaled in a bracket, n, on the top of the frame of the vane.

This frame p of the vane is provided with bearings $r-r'$, which connect the frame and its vane with the vertical tubular bearings aforesaid. The cords or chains pass down through the tubular bearings to a governor near the ground, which will be further described. From this tubular casting C projects forwardly a tapering bearing arm or axle for the wheel, and upon which the latter revolves. This wheel con-

sists of the long tapering hub s, from which the radial arms t extend, which are connected to one another by the rims u, having the right-angled flange v, to which are secured the oblique blade-holders w, to which said blades are secured.

The inner end of the hub is provided with a gear-wheel, E, which is cast in sections and bolted to the wheel in any suitable manner. 60 This gear-wheel meshes with a horizontal pinion, F, which is secured to the upper end of the vertical rod y, which extends near the ground for operating machinery, drawing water, &c.

The casting above referred to is further provided with two rods, z z, which extend laterally therefrom and parallel with the wheel, and at the outer ends of these rods is secured a vane, G, which projects beyond the wheel and serves as rudder to said wheel when the latter is out of the wind and keeps it in line therewith, thus preventing said wheel from revolving when out of gear.

One of the cords, k' , secured to the rear arm of the casting C, is secured at its lower end to a weight, H, which has a central vertical tube, I, through which passes the lower end of the other cord, chain, or wire, k, the end of which is swiveled to a hand-lever, J, which is pivoted at one end to the tower-frame. This weight serves as a governor, and can be increased, if desired, by applying additional weights to it, and when it is desired to throw the wheel out of the wind the operator simply bears upon 85 the hand-lever, thus drawing the cord or wire k, and causing the casting with its wheel to turn and the wheel to assume a parallel position to the main vane. Similar action is obtained by the weighted governor under heavy 90 winds, and the weight causes the wheel to again face the wind after a gale.

It will be seen that the axle or bearing for the wheel-hub, being tapering from the casting C to the end thereof, and being larger near the gear-wheel, tends to force the wheel against the wind, thus relieving the end shaft or tubular bearing from heavy pressure, and by arranging the wheel nearer to the center, as shown in the drawings, the wheel can be more quickly 100 adjusted to the wind and has not a great distance to travel in getting in and out of the

wind, and at the same time gives a uniform motion, and the rims being made of galvanized iron, with iron or wood blades secured to the wheel with the oblique portion, presents a durable wheel, and one that will not decay, as is the case with the rims made heretofore with mortises or slots to receive the blades, which cutting also weakens the rims; and it will be further observed that the anti-friction roller on 10 the casting C, traveling on the turn-table or flanged tubular bearing, receives the weight of said casting and wheel and permits both to shift in and out of the wind with ease, and that the casting and vane are independent 15 of one another in action, thus permitting the casting and wheel upon it to turn with perfect freedom and ease upon the turn-table, and that the vane is always held in line with the wind, while the wheel does the shifting or turning 20 out of the wind. At the same time it is durable, not liable to get out of order, and not expensive to manufacture. Should a gear-wheel break, the broken section could be readily replaced with a new section.

25 Having described my invention, what I claim, and desire to secure by Letters Patent, is—

1. The combination, in a windmill, of the tower B, the tubular portion A, braced and

flanged, as described, the flanged tubular casting C, bearing the arms h i and the axle of the wind-wheel, and also a roller, g, the cords k k', leading from the said arms around pulleys on the vane D, over pulleys m on the frame of this vane, and attached to a weight, 30 H, and lever J, the gearing which transmits rotation from the wind-wheel to the tubular shaft y, and the gearing at the lower end of this shaft, all as shown and described.

2. The combination, with the tower B, of 40 the main tubular support A, flanged at d e, and also flanged near its lower end, the braces therefor provided with turn-buckles, the tubular casting C, armed as described and carrying a wheel which bears on flange c, the vane-frame journaled on the tube A, and a bracket supported upon an upper extension of the vane-frame and bearing pulleys for the ropes 45 k k', all constructed and adapted to operate substantially in the manner and for the purposes described.

In testimony whereof I affix my signature in presence of two witnesses.

FRED A. BAKER.
